Specification of Letters Patent. Patented Aug. 18, 1914.

Application filed March 6, 1911. Serial No. 612,618.

To all whom it may concern:

Be it known that we, CHARLES E. SCRIBNER and FRANK R. McBERTY, citizens of the United States, residing at Jericho, in 5 the county of Chittenden and State of Vermont, and New Rochelle, in the county of Westchester and State of New York, respectively, have invented a certain new and useful Improvement in Printing-Tele- 10 graphs, of which the following is a full, clear, concise, and exact description.

This invention relates to printing telegraph apparatus, and the object is to produce a printed record upon a sheet of paper 15 by the use of a type carrier and a selecting apparatus controlled by two successive direct current impulses, that is, two current impulses separated by an interval of no current.

20 There is a type wheel on a motor driven shaft carrying a contact stop, like a radial arm, and there is a series of type magnets each having an armature stop which, when the magnet is energized, projects in the path 25 of the type wheel stop and halts the type in position to print at a common point by the impact of a press pad. The selecting apparatus consists of a local circuit with a series of parallel branches 30 divided into groups. Each branch contains the coil of a type magnet. These branches are again divided into groups, each group composed of one branch from each of the 35 first named groups, and the local selecting circuit is first closed through the terminal contact of one group, and then through a terminal contact of the other group to complete a circuit through the desired type magnet. When circuit is closed through the 40 desired type magnet the magnet projects its stop into the path of the radial arm and this contact closes a local circuit which, first, operates the press pad to print and then breaks the local selecting circuit to re- 45 store the parts to their normal and inactive position. The switches for closing the local selecting circuit are electromagnetic and each such electromagnet is provided with a holding coil which locks it in its closed position until released as described. Means are 50 shown and described for spacing between successive letters, for advancing the paper from line to line, for resetting the paper from one side margin to the other, for re-

setting the paper from an intermediate 55 point to the paragraph line and for shifting the type wheel from one row of type to another.

Certain features are disclosed in this application which are not claimed herein, but 60 which are disclosed and claimed in a co-pending application to F. R. McBERTY, Serial No. 700,767, filed May 31, 1912.

The accompanying drawings illustrate 65 the invention.

Figure 1 is a schematic view of the electromagnetic switches responsive to two successive direct current impulses which may be transmitted through two main lines, the essential elements of the recording apparatus for 70 stopping a type in position to print, for printing, and for restoring the selecting apparatus to a normal condition of rest; Fig. 2 is a view of the same electromagnetic switching apparatus and the complete 75 groups of local branches each containing a type magnet; and Fig. 3 shows the essential elements of the recording apparatus including the spacing and shifting apparatus with parts of the selecting apparatus not 80 appearing in Fig. 2. It is to be noticed that Fig. 3 is practically a continuation of Fig. 2, and by placing the drawings together circuits may be traced from one figure to the other. 85

There are shown two main lines L^1 and L^2 leading from a distant transmitting station Z at which the key 500 is arranged to transmit positive or negative impulses over either one or both of the main line conductors from grounded sources of energy 501 and 502. At the receiving station are located two polarized relays P and P^1 , one in each line, arranged to respond to positive current impulses only; two polarized relays 90 N and N^1 , one in each line, arranged to respond to negative impulses only; and a neutral relay Q connected in a ground branch common to both lines L^1 and L^2 . This relay responds to currents of either polarity in either line. Relay Q controls a movable contact b coöperating with fixed contacts 43 and 44. Suitable means are provided at the transmitting point for throwing upon either one line or the other, or both in multiple arc current impulses of either one polarity or the other in succession, that is, the impulses are separated by 100 105

an interval of no current. The circuit of line L^1 is traced via 10, coil 11, coil 12, coil 13 to ground 15; circuit of line L^2 is traced via 20, coils 21, 22, 23, to ground 15. Provision is made for causing the contacts of 5 relays simultaneously responding to impulses in two lines to engage with each other, as will be hereinafter described.

Each of the polarized relays is provided 10 with a locking coil a . Relay P controls a movable contact c engaging the fixed contact d . Relay P^1 controls the movable contact c^1 engaging the fixed contact d^1 ; relay N controls a movable contact c^2 engaging a fixed contact d^2 , and relay N^1 controls a movable contact c^3 engaging a fixed contact d^3 . The local selecting circuit is composed of a series 15 of parallel branches 40. These branches 40 are divided into five groups m^1, m^2, m^3, m^4, m^5 , and each group m^1-m^5 is provided with a terminal conductor n or n^1 . The branches 20 40 are divided into five other groups g^1, g^2, g^3, g^4, g^5 , each group consisting of branches from the five groups m^1-m^5 . The contact 25 terminal for each of the groups g^1 , etc., is a movable contact o controlled by a magnet as, q^1, q^2, q^3, q^4, q^5 . Each magnet q^1-q^5 is in a separate branch 50. Each terminal conductor n includes a holding coil a of one of the 30 relays P, P^1 , N, N^1 and terminates in a fixed contact 52, while terminal conductor n^1 is joined to one of the fixed contacts of relay v . An electromagnet x controls a series of movable contacts $y^1, y^2, y^3, y^4, y^5, y^6$, vibrating 35 between the contacts 51 and 52. Magnet x has a holding coil 53. Each branch conductor 50 containing the coil of an electromagnetic switch q^1-q^5 terminates in a contact stop 51. The conductor 55 shown as a heavy 40 line is a common battery wire supplied from battery at 56, 57, 58, or 59 according to the position of the relay armatures through which such battery is connected.

Assume that the letter F is to be printed, 45 and that for this purpose a positive impulse succeeded by a second positive impulse in line L^2 is transmitted. The first positive impulse attracts armature c , closes contact at d , and battery from 58 passes via $c^1, 72, c, d, 50, 51, 52, 53, 60, 61$ of the electromagnet switch h , 62, 194, 63, to ground at 64. The same impulse attracted armature b of the neutral relay Q closing circuit from ground at 67 via $b, 43, 45, 46$ of magnet h , battery 47 to ground. The armature 48 of magnet h is attracted, closing circuit from the common battery wire 55, via 48, 49, 65, coil 66 of magnet x to contact 44, and when the neutral relay Q releases its armature b at the 55 termination of the impulse contact is completed at 44 to ground at 67 through magnet x which attracts its armatures y^1-y^6 and locks itself through y^1 , contact 17, coil 53 to ground at 18. Spacer magnet S is operated, circuit being via grounded battery 250, 400,

251, coil of S, 252, 253, 254, 117 to ground at 255. This spacer magnet circuit is broken at 117 when magnet R is operating to reset carriage C. The second positive impulse in line L^2 now causes armature c to again engage 70 with d , circuit being from battery 58 via 72, $c, d, y^6, 52$, holding coil a of relay P, n , type magnet f , terminal contact o of group g^4 , conductor 73 to branching point 74, thence in multiple arc through the printing magnet 75, 175, armature 76 of magnet Y, back contact 77 to ground at 78, the other branch being via 74, 79, stop magnet 80 to ground 83. Magnet 80 withdraws its pawl 81 from the toothed wheel 82 releasing the motor driven 80 type wheel shaft s . The armature of printing magnet 75 carrying press pad 84 is attracted against the force of spring 85. This press pad 84 produces a printing impression 85 upon demagnetization of the coil 75, the paper sheet k being forced against the face of the type wheel when circuit is broken. The printing impression is taken under the following conditions: When the pawl 81 is withdrawn 90 from the toothed wheel 82, the radial arm 86 fixed on type wheel shaft s propelled by a motor, such as a spring w , rotates in the direction of the arrow, Fig. 1, and engages with the armature bar 87 of a type magnet. This armature bar 87 is attracted into the 95 plane of movement of the arm 86 by closing circuit through the type magnet (shown in dotted line at f , Fig. 3) as described. Upon engagement of the contact stop or arm 86 with the contact stop 87 a local circuit is 100 closed from ground at 90 via 86, 87, 91, coil of magnet Y to grounded battery 92. Magnet Y attracts its armature 76, breaking contact at 77, this deenergizes printing magnet 75 which releases press pad 84 to produce 105 the impression as described; this break is in one multiple arc branch and immediately following this action the magnet Y having also attracted its second armature 93, closes 110 circuit from the common battery wire 55, via 93, 94, coil of magnet V, 405 to contact 44, and if the main line is clear of controlling impulses to ground at 67. This can only occur when line L^2 is clear of the current impulses. Magnet V attracts its armature 63, 115 breaking contact at 194, and opening circuit through coil 61 of magnet h , conductor 60 and coil of q^4 . Magnets h and g^4 are thereupon deenergized releasing 120 their armatures. The deenergization of q^4 breaks the circuit which included the front contact of polar relay P, which was traced as follows: from grounded battery 58, via contact $c^1, 72, c, d, y^6, 52$, coil a of relay P, conductor n , type magnet f , terminal contact o of relay q^4 , conductor 73 to dividing point 74, through conductor 79, coil of stop magnet 80 to ground 83. This deenergizes polar relay P, type magnet f and stop magnet 80. Magnet h also releases its armature 48 which 125

falls away from contact 49, breaking circuit in conductor 65 and deenergizing magnet α . The parts resume their normal position of rest.

5 It is to be noticed that when the printing cycle is completed and the parts are to be returned to their normal position of rest, circuit conditions are initiated in the selecting circuit which are only completed by the 10 return of the neutral armature b to its back contact and this can only occur when the controlling impulses have ceased to exist in the coil of the neutral relay.

The type wheel t is provided with two 15 parallel lines of type; it is coupled to the shaft s , and is movable thereon. Normally it rests in its lower position where the upper row of type may be printed. When a character in the lower row is to be printed the 20 shift magnet p , Fig. 3, is operated and its armature 300, carrying a roller 301, engages with and raises wheel t and places the lower line of type in the printing position. There is an inking pad e pivoted at 302 and held 25 in engagement with the surface of the type wheel by spring 303.

The controlling impulses employed in the operation of the printing apparatus are positive or negative impulses in either line followed 30 in every case by a space and a positive or a negative impulse, and again, coincident impulses of the same polarity in both lines followed by a space and a positive or a negative impulse in one line or the other, or again 35 by two impulses of the same polarity in two lines followed by a space and two impulses of the same polarity in both lines. It results from this that there are six characteristic transmissible controlling impulses. Of 40 these, one characteristic impulse is reserved for a special purpose, to wit: the double negative impulse in lines L^1 and L^2 in multiple arc; it is employed to clear out and return to normal position of rest all magnets 45 in the selecting circuit. This leaves five characteristic impulses which may be used, any pair of which may be used alone, and results in a possible permutation of five times five or twenty-five different characteristic impulse combinations. Of these, one 50 is arbitrarily selected to perform a function auxiliary to the selection of a type magnet; to wit, the shifting of the type wheel or carrier bearing two parallel rows of impression 55 characters.

The polarized relays are arranged in pairs, those responding to the same polarity of line impulse being located in juxtaposition with coöperating and mechanically engaging contacts, located one on each armature bar. The armature bars are so pivoted and the contacts are so arranged with respect to each other that when the two armature bars are in their attracted position, the coöperating 65 contacts have each moved half way to-

ward each other to arrive at a common contact point. This is so in case of the double negative controlling impulses where the negative impulse is transmitted simultaneously on both lines connected in multiple arc, 70 which controlling impulse is used for restoring the selection circuit to its normal condition of rest as described. The double positive controlling impulse (that is, where a positive impulse is coincidentally transmitted on both lines followed by a space and the same positive impulses are repeated) is assigned to the function of shifting the type carrier from one row to the other with respect to the printing position.

Separate batteries 56, 57, 58, 59, etc., are shown to simplify the drawing, but a single grounded battery electrically connected with the armatures of the different polar relays would perform the same function.

The armatures of the relays N , N^1 make a separate contact when both are attracted by their magnets. Armature bar 30 is pivoted at 31 and carries a contact 32 to which it is mechanically united through the insulating material 33. Contact 32 is connected to ground at 34. Armature 35 pivoted at 38 carries contact 36 to which it is mechanically connected through insulating material 37 and the contacts 32 and 36 are in position 95 to contact with each other when both armatures are attracted simultaneously. The relays P and P^1 have their armatures similarly provided with contacts which engage when both are simultaneously attracted.

To reset the paper carriage C at the end of the printed line on the page, a negative impulse on both lines L^1 and L^2 to operate relays N , N^1 is transmitted; this closes the contact 106, circuit passing from ground 105 via 106, conductor 108, contacts 100, 101, closed by carriage C through coil 305 of release magnet R , battery 110 to ground 111. Holding pawl 112 is thereupon withdrawn from the ratchet 113 and spring actuated 110 toothed sector 114 returns the carriage to its opposite limit. A mechanical latch 115 locks the armature bar which controls holding pawl 112 retaining said pawl in its open position. When the carriage reaches its opposite extreme position it closes contacts 102 and 103 completing a circuit from ground 255 via 116, 118, conductor 119, 102, 103, 104, magnet T to common battery wire 55. This closes circuit through line space magnet T which attracts its armature 120 pivoted at 121.

There is an angular frame 131 pivoted at 121; it also carries the armature bar 120 and carries a pin 122 projecting through a slot 125 123 in the reciprocating, spring-retracted bar 124. On the bar 124 is a pin 125 projecting through a slot 126 in the link 127 pivoted at 128 to lever 129 by means of which its position is adjusted. The spring 130

130 retracts the frame 131 which carries the parts referred to, including the armature bar 120. The terminal of the bar 124 is shaped or constructed to engage with the paper and 5 may be equipped with any contact surface adapted to grip the paper *k* which passes between it and the coöperating terminal of the bar *i* pivoted at 132. The attraction of the armature and its bar 120 moves the bar 10 124 longitudinally to engage the paper and then moves the free terminals of the bars 124 and *i* upwardly carrying the paper upwardly between them. When the paper *k* has been carried to the upper feed limit it is 15 caught and held by suitable holding devices like dogs 133 on carriage C. The spring 130 retracts the frame 131 to its normal position.

The paper *k* is a sheet in form, supplied 20 from a roll (not shown) located below the carriage C; it passes up between the press pad 84 and type wheel *t*, which are shown moved to one side, so as not to obscure the view of other parts. The frame 131 is above 25 the carriage C and the end of the armature bar 120 is in position to engage the latch 115 and cause it to release the armature 225 of magnet R, which armature supports and controls pawl 112, which then reengages 30 with ratchet 113. As shown in Fig. 3, the paper *k* above the carriage, shown in dotted outline, has been turned edgewise so as to permit of clearly showing the feed bars 124 and *i* in their relation to the upwardly moving 35 paper.

For the purpose of paragraphing, the carriage is provided with means for returning 40 it to the paragraph line from any point in its advance movement, consisting of a separate winding 140 on the reset magnet R; this winding is included in a circuit controlled by the relay *r*. The relay *r* is operated by the relay *u* and the relay *u* is operated by a selecting branch circuit completed 45 in a manner similar to the completion of the circuit of any type magnet. To trace the course of this circuit it is to be understood that the paragraphing results from a positive impulse transmitted on both lines L¹ 50 and L² followed by a succeeding positive impulse on both said lines, and this is followed by the controlling impulses designed to actuate that type magnet, in the place of which the paragraphing controlling magnet 55 coil 140 is inserted by the operation of relay *r*. Let us assume the transmission of two positive impulses on both lines; this closes contact at 200, circuit passing from the common battery wire 55, via *y*⁶, 51, 50, magnet 60 *q*⁵, 60, coil 61 of magnet *h*, 62, 63 to ground at 64. Simultaneously contact is completed via ground 67, *b*, 43, 45, coil 46, 47 to ground. Both armatures of magnet *h* are attracted. 65 This closes circuit through the spacing magnet, as normally occurs on any type selection.

Relay *q*⁵ has attracted its armature and locked it in attracted position thereby locking relay *h* in attracted position; relay *q*⁵ has also attracted terminal contact *o* of group *g*⁵ with its supplemental armatures 70 201 and 202. The succeeding interval of no current allows the neutral armature *b* to fall back and close contact at 44, thus completing circuit through relay *x*, and locking it. This shifts the contacts *y*¹—*y*⁶ inclusive. 75 The second positive impulse on both lines L¹ and L² completes a circuit via 55, 200, *y*⁶, 52, 203, coil of relay *v*, conductor 60, 61, 62, 63 and 64. Relay *v* now locks itself, closing contacts at 204, 205 and 206; relay *v* closes local circuit from common battery wire 55 via 205, 207, coil 208, 209, 202 to ground. Magnet *u* attracts its armature 210 and circuit is closed from common battery wire 55, via contact 93 of relay *Y*, 211, and also via 80 55, 212, then 213 and coil 214 of magnet *u*, contacts 215, 210, through two multiple arc branches, one via coil 216 of magnet *r* to ground at 415, the other via conductor 217 and coil of shift magnet *p* to ground; this 85 shifts the type wheel from one row of type to the other; the lower row is now in position to print from. The operation of relay *r* has closed circuit from grounded battery 250 via armature 400, contact 401, conductor 95 402, contact 206, 201, conductor 404, coil of magnet *V*, conductor 405, back contact 44 of neutral relay *Q*. Upon the termination of the second positive impulse in L¹ and L² neutral relay *Q* is deenergized and closes the 100 above circuit to ground 67 through armature *b*. This energizes relay *V*, attracting armatures 63 and 212. The attraction of armature 63 breaks the circuit whereby relay *q*⁵ and relay *v* were locked, namely, from common battery conductor 55 through two multiple paths one via armature 204 of relay *v*, coil of *v*, the other via armature 406 of relay *q*⁵, coil of *q*⁵ and then via conductor 60, to coil 61, conductor 62, contact 194, armature 105 63 to ground 64. This causes magnet *q*⁵ and magnet *v* to release their armatures and also causes relay *h* to release its armatures, breaking the circuit of the spacer magnet *S* at the contacts 254, 253, and breaking the 110 circuit of the relay *x* at the contacts 49, 48 of relay *h*. The falling of magnet *q*⁵ and *v* break the circuit whereby magnet *V* was energized as just described, namely from ground through battery 250 to armature 400 of relay *r*, contact 401, conductor 402, contact 206 of relay *v* and 201 of relay *q*⁵, conductor 404, coil of *V*, conductor 405, contact 44, armature *b* of relay *Q*, to ground 115 67. This circuit is broken at the contacts 206, of relay *v* and 201 of relay *q*⁵, when these magnets are deenergized. 120

It is to be noted that the transmission of a positive impulse on L¹ and L² repeated twice with an interval of no current results 125 130

in leaving the following circuit locked after the other relays have been restored to their normal condition of rest: common battery wire 55 through armature 93 of relay Y and conductor 211 and in multiple arc through contact 212 of relay V, conductor 213, coil 214 of relay u, contact 215, armature 210, coil 216 of relay r to ground at 415 and the latter branch in multiple arc with conductor 217, and coil of shift magnet p to ground. This results in holding the shift magnet in its shifted position, bringing into position the lower line of type on the wheel; also in holding in its changed or energized position relay r which produces a circuit condition such that the impulses normally adapted for the energization of a type magnet for which coil 140 of magnet R has been substituted if sent over the line or lines when this relay r is in its energized position, will result in energizing coil 140 of reset magnet R. The type magnet here arbitrarily determined upon for this purpose corresponds to the letter M and, as determined upon in this particular instance, is controlled by the controlling impulses positive on L¹ followed by an interval of no current in either line, then by a negative impulse on L². The circuit when these impulses are sent immediately following the energization of the shift magnet p and the relay r resulting in the locked condition of shift magnet p and relay r just described, is as follows: Positive impulse on L¹ energizes polar relay P¹ and relay Q also responds. Relay P¹ closes circuit from battery 59, conductor 72, armature c¹ of relay P¹, front contact d¹, contacts y⁴ and 51, conductor 50, coil of relay q³, conductor 60, coil 61 of relay h, 62, 194, 63 to ground 64. The closure of this circuit results in the energizing magnet q³ and locking it. The simultaneous energization of relay Q resulted in the closure of the following circuit: from ground 67, through armature b, 43, 45, coil 46 of relay h, battery 47 to ground. Relay h attracted both armatures 48 and 253 and received through its coil 61, in the circuit of the magnet q³ just traced, sufficient current to hold it. The closure of circuit through armature 253 and conductor 254 by relay h results in completing the following circuit: from ground 255, through armature 117 of magnet R, 254, 253, 252, through coil of spacer magnet S, conductor 251 to the back contact of armature 400 of relay r. The circuit will be open at this point 400 and the spacer magnet S therefore cannot respond. The closure of armature 48 to contact 49 by relay h completed the following circuit: from common battery wire 55, armature 48 of relay h, 49, 65, coil 66, of relay x, contact 44, which is open until the termination of L¹ positive impulse under consideration. At the termination of this impulse, this circuit is completed, through armature b to ground 67; relay x will operate, closing a locking circuit from ground 18 through coil 53, contact 17, armature y¹, conductor 65, to common battery wire 55. Relay x will attract all armature contacts y¹ to y⁶ inclusive. The second impulse is negative on line L², relays N¹ and Q will respond. Relay N¹ closes the following circuit: from common battery wire 55, c³, d³, y², 52, coil a of relay N¹, conductor 311, armature 410 of relay r, 141, coil 140 of reset magnet R, 411, armature 412 of relay q³, 413, armature 414 of relay r to ground contact 415. The simultaneous operation of relay Q tended to close circuit through coil 46 of relay h, which had already been closed and locked. The circuit just traced through the coil 140 of reset magnet R causes it to attract its armature, withdrawing pawl 112 from engagement with the teeth of the ratchet 113 on shaft 417. The action of spring actuated sector 114 causes shaft 417 to revolve and gives to carriage C a return movement, closing, at the end of this movement contacts 102 and 103. The pawl 112 when withdrawn from the ratchet was held mechanically by latch 115 out of engagement with ratchet 113. The automatic closure of contacts 102, 103 by the rest of carriage C completes the following circuit: from common battery wire 55 through the coils of magnet T, conductor 104, 103, 102, 119, 118, armature 117 of magnet R to ground 255. The closure of this circuit energizes magnet T, which moves the paper from one line to the succeeding line as heretofore described, and this shifting movement also operates to withdraw the mechanical catch 115, to release pawl 112 which is then free to fall. The operation of magnet T also closes the following circuit: from ground through armature 120, of relay T, contact 418, conductor 91, coil of relay Y, battery 92 to ground. This operates relay Y which attracts armature 76 and 93. The operation of 76 performs no useful function at this time. The attraction of armature 93 removes one source of battery from the circuit which is holding relays u, r and shift magnet p. On its front contact the armature 93 of relay Y closes circuit from common battery wire 55 to contact 94 through coil of relay V, conductor 405, contact 44, armature b to ground 67. This energizes relay V which attracts its armature 212 and 63. The attraction of armature 212 removes the second source of battery from the circuit through conductor 213 which was holding relays u, r and shift magnet p in the energized position. They are therefore in open circuit upon the operation of relay V. The attraction of armature 63 breaks the circuit from ground 64, through 63, 194, 62, coil 61 of relay h, which

therefore falls, conductor 60 coil of relay q^3 to locking front contact of q^3 and common battery wire 55. Relay q^3 therefore falls. The falling of relay q^3 breaks the circuit previously traced from the front contact of polar relay N^1 through y^2 , 52, locking coil a of relay N^1 , 311, armature 410 of relay r , coil 140 of reset magnet R , conductor 411, contact 412 of relay q^3 , conductor 413, armature 414 of relay r , contact 415 to ground. This results in deenergizing polar relay N^1 and reset magnet R , which allows the pawl 112 to reengage with its ratchet. The deenergization of reset magnet R breaks the circuit from ground 255 through armature 117 and front contact 118, conductor 119, contacts 102, 103, conductor 104 and coils of magnet T to battery wire 55. Magnet T is deenergized and all parts of the circuit resume their normal position of rest.

The double negative controlling impulse, that is, a negative impulse thrown onto a circuit composed of both lines in multiple arc, operates the polarized relays N N^1 and the neutral relay Q . In operating the polarized relays N N^1 , it disconnects the source of current from the common battery wire and from this common battery wire the relays of the selecting local circuit obtain their locking current so that when the generator is disconnected, all locked relays are forced to assume a normal condition of rest. The double negative controlling impulse also operates the spacer magnet S to provide a space between words and when the paper carriage C is at or near the termination of its excursion from one side of the line of print to the other, and usually when it is within seven characters of the terminal, the carriage automatically closes the circuit of the reset magnet R the point 100, 101, and the next time the space key is depressed and the double negative controlling impulse is thrown upon the line, as for the purpose of spacing, it closes the second point in this reset magnet circuit so that the carriage is automatically returned to its starting point. The space bar in the transmitter operates contacts which throw this double negative controlling impulse on to the line as described, and it is the only key which employs the double negative impulse. The frequent use of the space bar, as customary in printing, results in the maintenance of the selecting circuit in a cleared condition, as at the beginning of each word, and insures the return of the paper carriage in due time.

To shift the type wheel and to print a character from the lower row of characters on the type wheel, there are transmitted certain controlling impulses which, exactly as in the previously discussed case of paragraphing, result in leaving the shift magnet p and relays u and r locked in an energized

position. These controlling impulses are then followed by the controlling impulses designated to energize the desired type magnet. Assuming that the character desired is the dollar sign, the sequence of operation is as follows: The shift key is depressed and released which results in sending on to the lines the two double positive impulses, that is to say, a positive impulse on both lines in multiple are followed by an interval of no current followed by a positive impulse on both lines in multiple arc. The result of the first double positive impulse will energize polar relays P and P^1 . It will also energize neutral relay Q . The contact 200 common to the polar relays P and P^1 will be closed, closing circuit from common battery wire 55 through contact 200, y^6 , 51, 50, coil of relay q^6 , 60, coil 61 of relay h , 62, 194, 63, to ground 64. This energizes magnet q^6 which locks itself through its armature contact 406. Simultaneously neutral relay Q has drawn its armature b against the contact 43, closing circuit via 67, b , 43, 45, coil 46 of relay h to grounded battery 47. Relay h therefore attracts its two armatures 48 and 253. By the circuit first traced relay h receives sufficient current in its coil 61 to hold its armatures in attracted position. The attraction of armature 253 closes the following circuit: from ground 255 through armature 117 of reset magnet R , 254, 253, 252, coil of spacer magnet S , 251, armature 400 of relay R to grounded battery 250. This operates spacer magnet S . The attraction of armature 48 of relay h closes the following circuit: from common battery wire 55, 48, 49, 65, coil 66 of relay α to back contact 44 of neutral relay Q . When the first controlling impulse terminates, neutral relay Q releases armature b and completes circuit through armature b to ground at 67, this circuit energizes relay α which attracts armature contacts y^1 to y^6 inclusive. Armature contact y^1 closes a locking circuit from ground 18 through coil 53, armature y^1 to conductor 65, contact 49 and armature 48 of relay h to common battery wire 55. The second double positive impulse, that is, positive impulses over both lines in multiple arc, will again energize polar relays P and P^1 and again close contact 200. This closes circuit from common battery wire 55, through contact 200, y^6 , 52, 203, coil of relay v , 60, coil 61 of relay h , 62, 194, 63 to ground 64. The completion of this circuit energizes relay v which locks itself by its armature 204. The armature contact 205 of relay v closes the following circuit at this time: from common battery wire 55 through 205, conductor 207, coil 208 of relay u , 209, 202 of relay q^6 to ground. This energizes relay u which attracts its armature 210. This armature closes the following circuit: from common battery wire 55, through contacts 130

in multiple arc, namely, armature contact 212 of relay V, armature contact 93 of relay Y and conductor 211, then conductor 213, coil 214 of relay u contact 215, armature 210 of relay u, then in multiple arc through coil 216 of relay r to ground contact 415 and through conductor 217 and coil of shift magnet p to ground. This energizes shift magnet p, displacing the type wheel, so as to bring into printing position the lower row of characters. The closure of this circuit also energizes relay r which attracts its armatures 410, 400 and 414. On breaking circuit at its back contact, the armature 400 of relay r breaks the circuit of the spacer magnet S which is thereby deenergized. The armature 400 of relay r closes the following circuit on its front contact: from grounded battery 250 through 400, 401, 402, contact 206 of relay v, contact 201 of relay q⁶, conductor 404, coil of relay V, conductor 405, back contact 44 of neutral relay Q. At the termination of the second double positive impulse, relay Q releases its armature and completes this circuit through its armature b to ground at 67. This energizes relay V which attracts its armatures 63 and 212. The attraction of armature 63 breaks the circuit from ground 64, through 63, 194, 62, coil 61 of relay h, conductor 60, coil of relays q⁵ and v in multiple to common battery wire 55. This releases relays q⁵, v and h. The release of armature 253 of relay h accomplishes no useful purpose. The release of armature 48 of relay h breaks the circuit of relay x which is thereby deenergized. The attraction of armature 212 of relay V removed one source of current for circuit through conductor 213, coil 214 of relay u, 215, 210, relay r and shift magnet p in multiple. This circuit still gets current through the back contact of relay Y and its armature 93. The deenergization of relays q⁵ and v broke the circuit through which, as already traced, relay V received its current as follows: grounded battery 250, armature 400, 401, 402, contact 206 of relay v, contact 201 of relay q⁶, conductor 404, coil of relay V, conductor 405, contact 44 of relay Q, armature b to ground 67, thereby deenergizing relay V and restoring all parts of the circuit to their normal position of rest, with the exception of the circuit through coil 214 of relay u and thence through relay r, and shift magnet p in multiple. We have now accomplished the purpose of the shifting operation and the shift magnet holds the type wheel in its changed position. A character is now to be printed, for example, the dollar mark. The dollar mark in the lower row on wheel t corresponds in position to the letter A in the upper row and the same characteristic controlling impulses will print either character, depending upon the position of the shift magnet. The controlling impulses employed are a positive impulse over both lines in multiple succeeded by an interval of no current and a positive impulse in L². The sequence of events is as follows: The positive impulse in both lines operates polar relays P and P¹ and neutral relay Q. Polar relays P and P¹ close common contact 200, completing the following circuit from common battery wire 55, through contact 200, y⁶, 51, 50, coil of relay q⁶, 60, coil 61 of relay h, 62, contact 194, 63 to ground at 64. This energizes the relay q⁵ which locks itself. Simultaneously neutral relay Q has operated, closing the following circuit: from ground 67 through armature b, 43, 45, coil 46 of relay h to grounded battery 47. Relay h is thus energized and practically simultaneously receives through its coil 61 sufficient current from the circuit of relay q⁵ just traced to hold its armatures in the attracted position. Relay h attracts its armatures 48 and 253 and armature 253 closes circuit of spacer magnet S, but this circuit remains open at the back contact of armature 400 of relay r owing to the attracted position of armature 400; magnet S is therefore not energized at this time. Armature 48 of relay h closes circuit from common battery wire 55 through 48, 49, conductor 65, coil 66 of relay x to back contact 44 of neutral relay Q. Upon the termination of this first impulse the neutral relay Q releases its armature which then completes circuit through armature b to ground 67. This causes relay x to attract armature contacts y¹ to y⁶ inclusive and close its own locking circuit through coil 53. The second impulse, which is a positive impulse on L², energizes polar relay P and neutral relay Q. Polar relay P attracts its armatures c and closes the following circuit: from battery 58 through armature c¹ of polar relay P¹, 72, c, d, through y⁵, 52, locking coil a of relay P, conductor n, through type magnet a¹, 73 to branching point 74, coil of printing magnet 75, 175, 76, 77 to ground at 78 and in multiple arc with this printing magnet circuit from 74 via 79, through coil of stop magnet 80 to ground at 83. The closure of this circuit results in locking relay P, energizing type magnet a' which raises its armature into the plane of the radial arm 86, attracting the armatures of printing magnet 75 and stop magnet 80. The stop magnet 80 releases ratchet wheel 82 and type shaft s rotates in the direction of the arrow, Fig. 1, until arm 86 engages type stop magnet 87. This results in stopping the type wheel with the dollar sign in position to yield an impression upon deenergization of printing magnet 75. The contact of arm 86 with type magnet stop 87 closes the following circuit: from ground 90 via type shaft s, arm 86, 87, 125

91, coil of relay Y to grounded battery 92. The printing magnet 75 is deenergized and relay V energized resulting in restoring all parts of the circuit to a normal position of 5 rest exactly as described when considering the operation of printing letter F. There is one point to be noted, namely, that the restoration of all parts of the circuit to their normal position of rest as a result of the 10 contact of the radial arm against the stop 87 includes the restoration to the normal position of rest of the shift magnet p and of relays u and r. This is due to the fact that relay Y first removes one source of current 15 for the circuit through conductor 213 and through relay u, thence through relay r and through shift magnet p in multiple, and that while this contact point at 93 is still open, relay V by attracting its armature 212, 20 removes the second source of current for this same circuit, thereby deenergizing relay u, which allows its armature 210 to fall away from its front contact 215, thereby permanently opening the circuit of relay r and 25 shift magnet p.

What we claim and desire to secure by Letters Patent is:

1. In a printing telegraph, the combination of a local selecting circuit having a plurality of branches, a type magnet in each said branch, switches for completing a circuit at each terminal of any type magnet branch, and electromagnetic self-locking means for actuating said switches responsive to two direct current impulses and an intervening interval of no current.

2. In a printing telegraph system, the combination of a plurality of conducting branches, a type magnet in each said branch, 40 an electromagnetic switch for closing contact on one side of a type magnet and locking said contact, an electromagnetic switch for completing said circuit on the other side of said type magnet and locking said contact, and means for controlling said switches by two direct current controlling impulses separated by an interval of no current.

3. In a printing telegraph system, the combination of a plurality of conducting branches, a type magnet in each said branch, an electromagnetic switch for closing contact on one side of a type magnet and locking itself, an electromagnetic switch for completing said circuit on the other side of said type magnet and locking itself, means for controlling said switches by two direct current controlling impulses separated by an interval of no current, and means for automatically unlocking said switches and returning said contacts to normal condition.

4. In a printing telegraph, the combination of a plurality of type magnets; a local selecting circuit branch for each said magnet; and means for completing a circuit

through any one branch, said means including two line wires, polarized electromagnetic switches in each line, a neutral electromagnetic switch common to both lines, and means for locking either polarized magnet in its energized position.

5. In a printing telegraph, the combination at a receiving station of a plurality of type magnets, a local circuit branch for each magnet, and means for closing any branch in response to two direct current impulses and an interval of no current, said means including polarized magnets responsive to said impulses to cause the closure of said local circuit branch at one point and a neutral relay responsive to said interval of no current to cause the closure of said branch at a second point.

6. In a printing telegraph, the combination of a plurality of type magnets, a local circuit branch for each said magnet, means for completing any one of said branches in response to two current impulses separated by an interval of no current, said means including two polarized electromagnetic switches and a neutral electromagnetic switch, and means whereby a polarized switch operates first to cause the closure of a break point, then the neutral switch operates to close a break point, and finally a polarized switch operates to complete said local circuit branch.

7. In a printing telegraph, the combination of a plurality of type magnets, local selecting circuit branches, one for each magnet, four polarized electromagnets, a neutral electromagnet having a plurality of windings, switches controlled by said electromagnets, and means for operating said electromagnets in pairs, successively, in response to two successive current impulses, each pair including one of the windings of said neutral electromagnet.

8. In a printing telegraph, the combination of a plurality of type magnets, local selecting circuit branches therefor, two polarized electromagnetic switches, a neutral electromagnetic switch, and means for operating said polarized switches coincidently to close one break point in said branches, then the neutral switch to close a second break point, then a polarized switch to complete said circuit.

9. In a printing telegraph system the combination of a plurality of branch circuits, arranged in groups; a type magnet in each branch circuit; and means for causing the energization of any one of all the said type magnets, said means comprising four polarized electromagnetic switches, a neutral electromagnetic switch, and means for operating said switches by two successive current impulses to close break points in any one of said groups of branch circuits in the

following order: first a polarized switch, second a neutral switch, third a polarized switch.

10. In a printing telegraph system the 5 combination of a plurality of branch circuits, arranged in groups; a type magnet in each branch circuit; and means for causing the energization of any one of all the said type magnets, said means comprising four 10 polarized electromagnetic switches, a neutral electromagnetic switch and means for operating said switches by two successive current impulses to close break points in said branch circuits in the following order: first a 15 pair of polarized switches, second a neutral switch, third a pair of polarized switches.

11. In a printing telegraph, a selecting circuit having a plurality of branches, two main terminals for controlling each of said 20 branches, a movable contact common to both terminals, controlling magnets consisting of polarized electromagnets and a neutral magnet, a connection from said movable contact to the armatures of said controlling magnets, 25 means for shifting said contact from one terminal to the other, electromagnetic switches, means for locking said switches in closed position in said branches, and means for operating a polar magnet to close a 30 switch and lock it, to shift said movable contact and lock it and to complete said circuit through the second main terminal and lock it.

12. In a printing telegraph, a rotary type 35 carrier, a plurality of selecting circuit branches, a type magnet in each said branch, electromagnetic locking switches controlled by two current impulses for closing a circuit through any branch to control the rotation 40 of said type carrier, a switch for said branches, a magnet to operate said switch, a circuit for said magnet, and means whereby the stoppage of the type carrier closes a circuit through said magnet to release said 45 locking switches.

13. In a printing telegraph, a combination of a rotating type wheel, a shaft therefor, a contact stop movable by said shaft, a plurality of type magnets, armature contacts 50 therefor in position to engage and hold said type shaft stop, a local circuit including said contacts, a magnet in said circuit, a selecting circuit, and a circuit breaker controlled by said magnet to break the selecting circuit 55 following the stoppage of the type shaft.

14. In a printing telegraph, a plurality 60 of conducting branches divided into groups, a type magnet in each said branch, a terminal contact for each group, electromagnetic switches for closing a circuit through one terminal in each of said groups, holding coils for said magnets, circuit connections for the holding coils, a switch for opening

said holding circuit, a magnet for operating said switch, a circuit for said magnet, a rotating type wheel shaft carrying a radial arm, a contact on said arm, a complementary contact, and means whereby a type magnet when energized blocks the movement of said radial arm, closes a circuit through said 70 magnet and opens said holding circuit.

15. In a selecting device for printing telegraphs, the combination of a plurality of conducting branches arranged in groups, a type-magnet in each said branch, line impulse 75 selected self-locking means for closing a break in any one of said groups of branches, groups of branch conductors composed of one branch from each of the first mentioned groups, and line impulse controlled self-locking means for closing a break in any one of said second mentioned groups, whereby any of said magnets may be selected by two line impulses.

16. In a selecting device for printing telegraphs, the combination of a plurality of conducting branches arranged in groups, a type-magnet in each said branch, a terminal conductor for each said group, a self-locking electromagnetic switch for each said conductor, groups of branch conductors composed of one branch from each of the first mentioned groups, a terminal conductor for each such second mentioned group, and self-locking switches for connecting the second 95 mentioned terminals to their respective second mentioned groups of branches, whereby any one of said magnets may be selected by two successive current impulses.

17. In a printing telegraph, the combination of a plurality of branches arranged in two sets of groups, contact terminals for each said group, a type magnet in each of said branches, a main switching apparatus for establishing a circuit to two group terminals in different sets in succession, means for operating said main switching apparatus by two successive direct current impulses, a switching device for allowing said main switching apparatus to control either of two 110 group contact terminals, respectively, means whereby the first current impulse closes one group terminal in one set, and means for shifting said switching device to the second terminal allowing the second impulse to 115 close a group terminal in a second set and complete the selecting circuit.

18. In a printing telegraph, a controlling circuit consisting of the combination of two conductors connected in multiple arc and to 120 a return conductor at the terminals, polarized relays in each conductor and a neutral relay common to both conductors, pairs of contacts for each relay, a local selecting circuit having a series of branches with a type 125 magnet in each branch, and local circuit

connections between said relay contacts and said branches.

19. In a printing telegraph, a controlling circuit consisting of the combination of two conductors connected in multiple arc and to a return conductor at the terminals, polarized relays in each conductor, a neutral relay in the return conductor, contact points controlled by said relays, a local selecting circuit having a series of branches, type magnets, one in each branch, and connections be-

tween said relay contacts and said local circuit branches.

In witness whereof, we hereunto subscribe our names this 28th day of February, A. D. 1911.

CHARLES E. SCRIBNER.
FRANK R. McBERTY.
